UNITED STATES PATENT OFFICE.

WILLIAM O. SMITH, OF CAMBRIDGEPORT, MASSACHUSETTS.

WOOD-MOLDING MACHINE.

SPECIFICATION forming part of Letters Patent No. 289,319, dated November 27, 1883.

Application filed May 3, 1883. (No model.)

To all whom it may concern:

Be it known that I, WILLIAM O. SMITH, a citizen of the United States, residing at Cambridgeport, in the county of Middlesex and 5 State of Massachusetts, have invented certain new and useful Improvements in Wood-Molding Machines; and I do hereby declare that the same are fully described in the following specification and illustrated in the accompanying 10 drawings.

This invention relates to improvements in irregular molding-machines for shaping wooden articles—such as brush-handles and articles of a kindred nature—and it is carried out as follows, reference being had to the accompanying 15 drawings, where—

Figure 1 represents a plan view of the improved machine. Fig. 2 represents a central longitudinal section of the same as seen from 20 A in Fig. 1. Fig. 3 represents a cross-section on the line A B, shown in Fig. 1. Fig. 4 represents a cross-section on the line C D, Fig. 5 represents a cross-section on the line E F, and Fig. 6 represents a cross-section on the 25 line G H, all shown in Fig. 1. Fig. 7 represents in detail a side elevation of the longitudinally-movable work-holder.

Similar letters refer to similar parts wherever they occur on the different parts of the 30 drawings.

a represents the stationary frame or bed, to which the upright bearings *b b* are attached.

c is the rotary cutter-shaft, supported in the bearings *b b*, and provided with the belt-pulley *c'*, to which a rotary motion is imparted 35 by means of belt-power, as usual.

d d are the expansive cutter-heads, to which the cutters *e e* are secured by means of screw-bolts *e' e'*, as shown.

40 *c'' c''* are keys secured to shaft *c*, which keys project into corresponding key-beds in the expansive heads *d d*, so as to admit the latter to be easily moved to and from each other on the shaft *c*, and to rotate with the latter.

45 *f* is the longitudinally-movable work-supporting carriage, which has grooved sides *f' f'*, and is guided between the longitudinal guide-pieces *g g'*, which are secured in an adjustable manner to the top of the bed *a*, as shown in 50 the drawings. The under side of the carriage *f* is provided with the cog-rack *f''*, into which

is geared the pinion *h*, secured to shaft *h'*, as shown. The shaft *h'* is located in a bearing, *h''*, secured to the under side of the stationary bed *a*, and is provided with a crank-wheel, *h''*, and cranks *h''*, as shown in Figs. 1, 2, and 6, or in a suitable or equivalent manner, so as to impart a reciprocating motion to the carriage *f*, by turning the shaft *h'*, by means of its crank, in opposite directions. The cutter-heads *d d* 60 are automatically moved to and from each other, to impart the proper shape to the wooden handle, by the following mechanism, viz:

On the inside of each bearing *b* is secured a bracket or arm, *i*, to which is hung, at *i'*, the 65 downwardly-projecting lever *i''*, the lower end of which is actuated by the inclined bar *k*, that is secured to the top of carriage *f* by means of set-screws *k' k'*, passing through slot-holes *k'' k''* in the ends of the bars *k*, so that they 70 may be adjusted to and from the center of the machine, according to the desired shape to be given to the wooden handle or other article that is being made.

To the upper end of each rock-lever *i''* is secured a tooth or projection, *i''*, that is made, preferably, of hardened rawhide, to reduce friction, such tooth projecting into an annular groove, *d'*, on each cutter-head *d*, as shown in Fig. 3, and it will thus be seen that the heads *d d* 75 are automatically expanded from each other during the forward motion of carriage *f* by the inclined bars *k k* coming in contact with the outer edges of the lower ends of the rock-levers *i'' i''*, causing said levers to rock on their 80 respective fulcra *i' i'*, and their upper rawhide projections, *i'' i''*, to expand from each other and to carry with them their respective cutter-heads *d d* against the influence of the coiled springs *d'' d''*, the ends of which are secured 85 in a suitable manner to the heads *d d*, as shown in Fig. 3, and which springs *d'' d''* are made of sufficient strength to automatically pull the heads *d d* toward each other when the rock-levers *i'' i''* cease to expand them, and in this 90 manner the cutter-heads *d d* and their respective cutters are automatically moved to and from each other during the feed of the work, so as to produce the desired curvature or taper, which is determined by the position of the 95 bars *k k* on the sliding work-supporting carriage *f*.

The device for securing the work during the operation of shaping it is as follows: To the top of the sliding carriage f is firmly secured the head-stocks l and m , the latter being adjustable to and from the former by means of set-screw m' , which passes up through slot-hole f^3 , and is screwed into the under side of the adjustable head-stock m , as shown in Fig. 2. The stationary head-stock l has a vertical perforation, l' , in which the cylindrical shank l'' of the head l^3 is vertically adjustable and caused to be held down by means of the weight l^4 , secured to rod l^5 , the upper end of which, after passing loosely through carriage f , is screwed into the under side of the shank l'' .

l^6 is a coiled spring surrounding the rod l^5 between top of weight l^4 and under side of carriage f , as shown in Fig. 2, which spring aids in drawing the shank l'' downward; but said spring is not essential, and may be dispensed with, if so desired, and the weight l^4 increased proportionately.

In the upper end of the stationary head-stock l is a vertical recess, l^7 , in which rests loosely the shaping-bar n , the upper edge of which has an irregular surface, n' , corresponding to the shape to be given to the top and bottom of the articles operated upon. The bar n is hung in its rear end, at n'' , to the standard n^3 , secured to top of frame a , as shown in Fig. 2.

In the head l^3 is located the centering-pin o , with outer centering projections, $o'o'o''$. (Shown in Figs. 1 and 2.) The centering pin o is free to turn around its axis in its horizontal bearing in the head l^3 , and is retained in the latter by means of pin o^3 , projecting into an annular groove on the inner end of pin o , as shown in Fig. 2.

Through the shank l'' is made a lateral perforation, l^8 , through which the shaping bar or lever n passes loosely, the upper end of such perforation l^8 being provided with a steel pin, l^9 , firmly secured to shank l'' , and adapted to rest on top of bar n and to be held in contact with the latter by means of the weight l^4 and spring l^6 , before mentioned, during the reciprocating motion of the carriage f .

p is a set-screw screwed through one side of stationary head-stock l , and having its inner end projecting into a vertical groove, p' , in the side of shank l'' , so as to prevent the latter from turning around its axis within the hollow head-stock l , as shown in Fig. 4.

The adjustable head-stock m has a vertical perforation, in which the cylindrical shank m'' of the hollow head m^3 is vertically adjustable and adapted to be secured by means of set-screw m^4 , the inner end of which projects into a vertical groove, m^5 , on the shank m'' , to prevent the said shank m'' and its head m^3 from turning around within the hollow head-stock m while being adjusted.

Within the hollow cylindrical head m^3 is the hollow sleeve m^6 , adjustable in a horizontal direction, and is prevented from turning around its axis by the key m^7 , projecting in

corresponding grooves in the bore of the head m^3 and exterior of sleeve m^6 , as shown in Fig. 5.

Within the sleeve m^6 is located the centering-spindle q , having enlarged head q' , terminating as a centering tooth or projection, q'' , in its inner end, as shown in Figs. 2 and 7, between which and the centering projections $o'o'o''$ on the centering-pin o the wood blank is held during the operation of shaping it. The spindle q is moved, with the sleeve m^6 , in a horizontal direction within the hollow head m^3 , for the purpose of locking and releasing the wood blank between its centering-pins by means of the bent lever or handle r , the upper end of which is hinged at r' to the link r'' , hinged at r^3 to the outside of the hollow head m^3 , as shown in Figs. 1 and 7. The inner bent end of the lever or handle r is hinged at r^4 to the rear end of the sleeve m^6 , as shown in Fig. 1 and in dotted lines in Fig. 7, by which arrangement the sleeve m^6 and its spindle q are drawn backward by raising the bent lever r on its fulcrum r^3 , so as to release the wood blank from its centers after being shaped, and to move said spindle and sleeve forward to the position shown in Figs. 1 and 7, to secure the wood blank between its centers, by turning the bent lever r and its connecting-link r'' to 95 the locking position shown in said Figs. 1 and 7. After the upper side of the wood blank has been shaped, it is desirable to turn it on its supports half a revolution, and to hold it in such a position for finishing its opposite side, and for this purpose I provide the rear end of spindle q with a handle, q^3 , by means of which the said spindle can be turned around its axis, and a locking-hub, q^4 , having one or more locking projections, q^5 , adapted to fit into corresponding notches, m^7 , in the rear end of sleeve m^6 , as shown in Figs. 1 and 2.

q^6 is a coiled spring surrounding the rear end of the spindle q , between the handle q^3 and the locking-piece q^4 , so as to hold the latter automatically in a locked position in relation to the sleeve m^6 , as shown in Fig. 1.

The locking-piece q^4 has secured to it a peg or handle, q^7 , the inner end of which projects into a slotted recess, q^8 , in the spindle q , as shown in Fig. 2, said recess or groove q^8 being made long enough in the longitudinal direction of the spindle q to enable the locking-piece q^4 to be moved backward on the spindle q by manipulating the handle q^7 , so as to disengage the locking projections q^5 from the notches m^7 on the sleeve m^6 , to enable the spindle q to be turned half a revolution on its axis and to be retained in that position, and thus to turn the wood blank (which is held between the centering-points of the two head-stocks aforesaid) half a revolution around its axis, to shape its opposite side after the first side of it has been molded or shaped by the cutters.

a' is a slot through the frame a , to enable the rod l^5 to have a free passage as the carriage f

is moved forward and back during the operation of the machine.

8 is an adjustable stop projection, secured to guide *g* by means of screw *s*', to prevent the carriage *f* from being moved too far forward, thereby preventing the cutters *e e* from coming in contact with the forward end of spindle *q* and its head *m*'.

9 *t* is an adjustable bracket secured to carriage *f*, and has hinged to it the lever *t*', provided with rest projection *t*'', which serves as a centering-gage for the wood blank when the lever *t*' is turned upward.

10 *u u* are standards secured to carriage *f*, and 15 having their upper ends connected to pin *u*' on the head *l*' by means of the coiled springs *u*'' *u*''', so as to relieve the frictional resistance between the shank *l*'' and hollow head-stock *l* when the work is clamped between its center 20 ing-spindles.

25 The operation of the machine is as follows: Before the wood blank that is to be shaped is placed between the centering-points of the head-stocks *l m*, the carriage *f* is moved by means of rack and pinion *f*'' *h* to the limit of its stroke toward the right in Fig. 2, and the wood blank is then secured between the centering-points of the head-stocks *l m*, in the manner as described. The cutter-shaft *c*, with 30 its cutter-heads *d d*, is then set in a rotary motion, and the carriage *f*, with its head-stocks, is moved toward the left in Fig. 2 by means of the rack, pinion, and crank, as described, the stationary irregular bar or lever *n* causing 35 the head-stock shank *l*'', with its centering-pin *o*, to rise and fall, so as to produce the desired curvature on top of the wood blank by its contact with the rotary cutters *e e*, the latter being automatically moved to or from each 40 other by the action of the adjustable guides *k k* on the rock-levers *i'' i'''*, having the rawhide teeth *i'' i'''*, engaging into the grooves *d' d'* on the heads *d d*, with its springs *d'' d''*, for the purpose of giving the desired taper or curvature 45 to the sides of the wood blank. After the top of the wood blank has been shaped, it is turned half a revolution on its centering-spindles and the opposite side shaped like the first, when it is detached from the centering-spindles and a new one inserted, and so on.

Having thus fully described the nature, construction, and operation of my invention, I wish to secure by Letters Patent and claim—

1. The combination, in a molding-machine,

of a frame, *a*, a reciprocating carriage, *f*, carrying a center, *q*, and a rising and falling center, *o*, a pattern, *u*, for moving vertically the center *o*, a cutter-shaft, *c*, two cutter-heads, *d*, each carrying cutters *e* and keyed to the shaft to move longitudinally thereon, and devices 60 connecting the cutter-heads with opposite sides of the reciprocating carriage to move the cutter-heads away from each other by the sliding movement of the carriage, substantially as described.

65

2. The combination, in a molding-machine, of the reciprocating carriage *f*, the guide-bars *k*, arranged on the upper side of the carriage, means for adjusting the bars toward and from each other, the cutter-shaft *c*, the cutter-heads *d*, keyed to the shaft and having annular grooves *d'*, the pivoted levers *i''*, having teeth at their upper ends arranged in the annular grooves of the cutter-heads, and their lower ends adapted to be acted on by the guide-bars 75 on the carriage to move the cutter-heads away from each other, and a spring connecting the cutter-heads to draw them toward each other, substantially as described.

3. The combination, in a molding-machine, 80 of the reciprocating carriage *f*, the hollow stock *l* thereon, the head *l*', carrying the center *o*, and having the shank *l*'', provided with the transverse opening *l*^, the pattern-bar *n*, pivoted at one end and passing through the 85 opening *l*^, and the weight *l*^, having a stem, *l*^, passing through the carriage into the stock, and attached to the lower end of the shank *l*''; substantially as described.

4. The combination, in a molding-machine, 90 of the reciprocating carriage *f*, carrying the stocks *l* and *m*, the head *l*', having the shank *l*'', arranged in the stock *l*, the center *o*, keyed to rotate in the head, the hollow head *m*', having a shank, *m''*, arranged in the stock *m*, the 95 sleeve *m*^, the center *q* in said sleeve, and having a head, *q*', the pivoted lever *r*, connected with the sleeve *m*^ to move the center *q* longitudinally, and the handle *q*^, connected with the outer end of the center *q* to rotate the latter, substantially as described.

In testimony whereof I have affixed my signature in presence of two witnesses.

WILLIAM O. SMITH.

Witnesses:

ALBAN ANDRÉN,
HENRY CHADBOURN.
